UNITED STATES PATENT OFFICE.

ISAAC B. POTTS, OF COLUMBUS, OHIO.

PIPE-WRENCH.

SPECIFICATION forming part of Letters Patent No. 249,394, dated November 8, 1881.

Application filed September 24, 1881. (No model.)

To all whom it may concern:

Be it known that I, ISAAC B. POTTS, of Columbus, in the county of Franklin and State of Ohio, have invented a new and Improved 5 Pipe-Wrench, of which the following is a full, clear, and exact specification.

Reference is to be had to the accompanying drawings, forming part of this specification, in which similar letters of reference indicate corresponding parts in all the figures.

Figure 1 is a side elevation of my improved pipe-wrench. Fig. 2 is a plan view of the same; and Fig. 3 is a cross-sectional elevation taken on the line $x-x$ of Fig. 1.

15 A represents the main bar, which is extended to form the handle b and bent down at the forward end to form the fixed jaw a, and is formed upon the under side with the notches c; and B represents the movable jaw, which is held under the main bar by means of the sliding saddle or yoke C, which saddle or yoke is adapted to be raised or lowered by the set-screw d, for engaging and disengaging the lip e, formed on the rear end of the movable jaw, with and from 20 the notches c of the main jaw.

The forward end or face f, of the movable jaw is inclined from the top backward, and is formed

with the downwardly-inclined teeth, as shown in Fig. 1, while the main fixed jaw a is inclined in the opposite direction, and is formed with 30 the teeth g, which are inclined upwardly, as also clearly shown in Fig. 1. By this opposite inclination of the faces of the jaws the bite of the tool upon the pipe or rod and its disengagement therefrom are automatic, depending 35 solely upon the up-and-down movement of the lever, thus dispensing with all separate mechanism for that purpose and all necessity for gripping any levers with the hands.

Having thus described my invention, I claim 40 as new and desire to secure by Letters Patent—

The combination, with the bar A, provided with the inclined and serrated stationary jaw a at its outer end and the notches c on its under side, of the yoke or saddle C, the thumb-screw d, and the movable jaw B, secured at each 45 end to the said yoke or saddle, and provided with the lip e and the serrated face f, inclined in an opposite direction to that of jaw a, substantially as and for the purpose set forth.

ISAAC BROADWORTH POTTS.
